UNITED STATES PATENT OFFICE.

LUIS ESTRADA, OF BUENOS AIRES, ARGENTINA.

WINDOW.

Application filed September 19, 1925. Serial No. 57,401.

The present invention relates to windows; and it involves certain improvements, hereinafter fully described, whereby the sash or sashes may be moved into the interior of the room in which the window is located to enable the outer face or faces thereof to be readily cleaned.

According to the invention, an auxiliary frame containing the sash or sashes is mounted in a stationary main frame secured in the window opening, and is designed to move relatively to the latter frame in a direction to bring the sashes within the room, such movement preferably taking place about a vertical axis. The side members of the sash or sashes are preferably connected by upper and lower pairs of links to the corresponding side members of the auxiliary frame to enable the sash to swing bodily between a position in which it is disposed wholly within the frame and one wherein it is disposed wholly outside of and spaced from the frame; the upper pair of links being made appreciably shorter than the lower pair so as to enable the sash to swing outwardly and downwardly of its own weight into open position when released. The several pairs of links are connected at one end to forks carried by brackets secured to the side members of the auxiliary frame; and these forks are preferably provided with threaded stems which fit rotatably and adjustably in sockets formed in the brackets in order to permit a slight vertical change in the height of the pivot points to be obtained.

In the accompanying drawings forming a part of this specification:

Figures 1 and 2 are diagrams showing a sash mounted in accordance with my invention in closed and open positions, respectively;

Fig. 3 is a view similar to Fig. 2, but showing a slightly different arrangement of the supporting brackets;

Fig. 4 is a diagram showing two superposed sashes equipped with a device for operating them simultaneously;

Figs. 5 and 6 are enlarged detail views of two forms of brackets;

Fig. 7 is a front elevation of a complete window, with both sashes closed;

Fig. 8 is a central vertical section of Fig. 7, but also showing in dotted lines the sashes and auxiliary frame in open position.

Referring more particularly to the draw-

ings, 1 indicates the window opening in the wall of a room or the like, and 23 the main window frame which is suitably fixed therein and which may itself be of any preferred construction. Within frame 23 is mounted an auxiliary frame 25 which is adapted to swing relatively thereto about a vertical axis; and this frame 25, in turn, contains a pair of superposed sashes 24 which are movable relatively to the frame and to each other (or, if preferred, there may be a single sash only disposed in the frame). In the arrangement illustrated in Figs. 7 and 8, the auxiliary frame 25 is hinged along one of its vertical side edges, as indicated at 26, to the adjacent vertical side member of the fixed or main frame 23.

The sashes 24 (assuming that two are utilized, as represented in Figs 7 and 8) are designed to move bodily into and out of frame 25; their outward movement preferably taking place automatically when the sashes are released, due to the weight of the sashes and to the special mounting illustrated in detail in Figs. 1-6. Each sash, as therein shown, is supported by upper and lower differential arms 4 and 7; the shorter upper arms 4 being pivoted at their upper ends at 5 to the side members of the sash and at their lower ends at 6 to brackets 15 secured to the corresponding members of the frame 25, while the longer lower arms 7 are pivoted at their upper ends at 8 to the sash sides and at their lower ends at 9 to similar brackets fastened to the frame sides. The several brackets 15 may be attached either to the inner faces of the frame sides (Figs. 1 and 2) or to their rear faces (Figs. 3 and 4), and they are formed with screw holes 16 (Figs. 5 and 6) for the insertion of the fastening screws therethrough. These brackets, moreover, are equipped with forks 18 having threaded stems 17 which are adjustably engaged in threaded openings or sockets formed vertically in the brackets so that the forks may be raised or lowered. This vertical adjustment of the forks may be effected simply by rotating the fork itself (Fig. 5) or by forming a key opening 21 (Fig. 6) through the bottom of the bracket to enable a key to be engaged with the squared or otherwise shaped end 22 of the stem 17. The inner ends of the links 4 and 7 are designed to be pivotally secured in the forks, and for that reason the latter are perforated, as indicated at 20, to permit suitable

115

pivot pins (not shown) to be passed therethrough and through registering perforations in the link ends; the vertical adjustability of the forks enabling a certain vertical regulation of the points of pivotal connection of the links to the frame.

In the construction illustrated in Fig. 4, means are provided for operating both sashes simultaneously; such means embodying a vertical rod 14 which is pivotally connected at 13 to the free ends of angular extensions 12 of the lower sash links 7. The brackets 15 in this form of the invention are replaced by brackets 10 of slightly different shape which, however, may be, and preferably are, provided with forked portions wherein the links 6 and 7 are pivoted, as before.

I claim as my invention:

20 1. A window, comprising a stationary main frame, an auxiliary frame mounted in and movable relatively to the main frame, brackets secured to the side members of the auxiliary frame, vertically adjustable forks mounted in said brackets, a sash, and upper and lower link connections between said forks and the corresponding side members

of the sash to enable the latter to move bodily out of and into the auxiliary frame; said auxiliary frame being movable in a direction 30 to bring the sash into position to enable its outer surface to be cleaned from within the interior of the room wherein the window is located.

2. A window, comprising a frame, 35 brackets secured to the side members thereof, vertically adjustable forks mounted in said brackets, a sash, and upper and lower link connections between said forks and the corresponding side members of the sash to enable the latter to move bodily out of and into said frame.

3. A window, comprising a frame, brackets secured to the side members thereof, vertical forks having threaded stems 45 which are rotatably and adjustably mounted in threaded vertical sockets formed in the brackets, a sash, and upper and lower link connections between said forks and the corresponding side members of the sash to enable the latter to move bodily out of and into said frame.

In testimony whereof I affix my signature
LUIS ESTRADA
